UNITED STATES PATENT OFFICE.

JOHN W. JAMES, OF PRICE, UTAH.

ADJUSTABLE STOVEPIPE-HOLDER.

1,110,938.

Specification of Letters Patent. Patented Sept. 15, 1914.

Application filed September 26, 1913. Serial No. 792,015.

To all whom it may concern:

Be it known that I, JOHN W. JAMES, a citizen of the United States, residing at Price, in the county of Carbon and State of Utah, have invented new and useful Improvements in Adjustable Stovepipe-Holders, of which the following is a specification.

This invention relates to improvements in stove pipe holders and has for its primary object the provision of a holder whereby both the vertical and horizontal sections of the stove pipe are rigidly supported with respect to the chimney.

Another object of the invention is the provision of a device of the above-mentioned character which is capable of adjustment to accommodate pipes whose horizontal portions are of different lengths and to this end I provide a device including a plurality of telescopic sections.

A further object of the invention is the provision of a device of the class in question with means by which the device is effectively sustained by the walls of the smoke flue and said means being adjustable to permit of its use with different size flues.

A still further object of the invention is the provision of a holder comprising adjustable members, one of which is effectively sustained in position by the walls of the chimney and which projects through the flue opening for connection with the pipe, and a flexible adjustment by which the holder may be tilted to permit the insertion of the horizontal section of the pipe within the flue opening.

I further aim to provide a device of the class described provided with means whereby the device may be tilted upwardly to permit the insertion of the horizontal section of the stove pipe within the flue opening, and automatically return the device to its normal position.

A still further object of the invention is the provision of a stove pipe holder which is effectively sustained in position by the walls of the smoke flue and adapted to support both the vertical and horizontal sections of the stove pipe and so connected therewith that the pipe may be removed from the holder without disconnecting the sections or disturbing the holder.

Another object of the invention is the provision of a device of the character described comprising comparatively few parts which may be readily assembled or disassembled,

as the occasion may demand, and which may be quickly fitted or removed from the flue.

With these and other objects in view which will appear as the nature of the invention is better understood, the invention resides in the specific construction, combination and arrangement of parts which will hereinafter be more fully described and particularly pointed out in the accompanying claims.

In the drawings forming a portion of this specification and in which like numerals of reference indicate similar parts in the several views: Figure 1 is a side elevation showing the holder in its applied position, a portion of the chimney and stove pipe being broken away. Fig. 2 is a perspective view of the holder detached. Fig. 3 is a detail view of the inner adjustable tube of the holder. Fig. 4 is a sectional view taken on the line 4—4 of Fig. 3. Fig. 5 is a detail sectional view taken on the line 2—2 of Fig. 1. Fig. 6 is a longitudinal sectional view through the holder, showing the method of anchoring the device to the chimney. Fig. 7 is a longitudinal sectional view through the holder showing the same in operative position. Fig. 8 is a view showing the holder including a plurality of telescopic sections.

Referring to the drawings by numerals, 1 designates the vertical sections of a stove pipe which are connected with the horizontal section 2 by means of the elbow 3.

The improved holder forming the subject matter of this invention comprises as illustrated in one embodiment thereof an outer hollow member 4 of substantially rectangular formation having its bottom wall longitudinally slotted, as at 5. The said outer member 4 is effectively sustained in operative position by the walls of the smoke flue 6, one end of the member 4 being seated in a suitable recess 7 in the rear wall 8, while the opposite end of the said member projects through the flue opening 10 a considerable distance beyond the chimney breast 11 and is connected with the horizontal section 2 of the stove pipe, in a manner hereinafter described.

Arranged for sliding adjustment within the member 4 is an inner member 12 of approximately half the length of the outer member 4 and of a configuration corresponding to that of said outer member. The said inner member has its upper wall provided with a longitudinal slot 13 which is arranged directly beneath the upper wall of

said outer member 4. Passing through a suitable opening in the said upper wall of the outer member 4 and through the slot 13 of the inner member is a thumb screw 14 having a nut 15 threaded thereon and arranged within the said inner member, and by means of which said inner member is held in adjusted position. The bottom wall of the said inner member is provided with openings 16 and 17 adjacent its opposite ends and passed through the said opening 16 is an angular shaped rod 18, the purpose of which will be presently described. The said rod 18 in the present instance is substantially Z-shaped, the vertical portion 19 of which passes upwardly through the slot 5 of the outer member and the opening 16 of said inner member. One end of the said rod is arranged within the said outer member, being extended rearwardly beyond the said inner member, while the opposite end of the said rod is extended in a forward direction and terminates in a point which is adapted to be embedded in the breast of the chimney with a view of rigidly supporting the device properly positioned with respect to the flue openings therein. It will be noted that when the device is so positioned the same will rest on the bottom wall of the said flue opening.

With a view of providing a flexible adjustment by means of which the device may be tilted vertically so as to permit the insertion of the horizontal portion of the stove pipe within the flue opening, after the holder has been positioned in the chimney as hereinabove described, I employ a leaf spring 20 which has one end rigidly secured in any suitable manner between the walls of said inner member, while the free end of the said spring projects rearwardly from the upper wall of said inner member a considerable distance beyond the end thereof. The body portion of the spring is spaced from the upper wall of said inner member and normally engages the said bar 18 so as to effectively retain the latter in engagement with the breast of the chimney. By reason of the fact that the said inner and outer members are connected together, it is obvious that the entire device may be tilted upwardly against the tension of the spring 20 away from the bottom wall of the flue opening to permit insertion of the horizontal section of the stove pipe within said opening, and after which the said spring operates to automatically return the device to its normal position. The horizontal portion of the pipe is provided with suitable openings 21, through which are extended screw bolts 22 provided with nuts 23. The openings 21 are arranged to register with the slot 5 of the outer member so that when the pipe is being inserted within the flue opening the screw bolts 22 enter the slot 5, and after the pipe

is properly positioned within the said flue opening the screws are tightened to rigidly connect the pipe and holder together.

The outermost of said screw bolts 22 has connected thereto one end of a flexible element 24. The element 24 has its opposite end connected with a hook 25, and the said hook as well as the element 24 is passed through the elbow and pipe sections, so that the hook 25 may be passed between the joint of one of the vertical sections of the pipe and secured to the lower end thereof. The flexible element is constructed from resilient material so that when the hook 25 is properly positioned the element 24 will exert a tension between the hook and screw bolt to which it is attached to retain the hook in effective engagement with the vertical section. By reason of the connection between the pipe and holder it is manifest that when taking down the pipe it is only necessary to loosen the screw bolt 22 when the entire pipe may be removed from the holder and carried out doors before disconnecting the sections or without disturbing the holder.

26 indicates a removable handle adapted to be inserted within the opening 17 in the bottom wall of the said inner member, and by means of which the said inner member may be adjusted so as to fit the device to different size flues.

To put up a pipe with my improved holder you first loosen the thumb screw 14, slide the inner member rearwardly by means of the handle 26 until the rod 18 drops down inside the chimney. The said outer member is then in a position whereby one end thereof will engage within the recess in the back wall of the chimney and the opposite end extends horizontally out into the room, while the intermediate portion rests on the bottom wall of the flue opening in the chimney breast. The said inner member is then drawn forwardly by means of the handle 26 until the rod 18 strikes the inner wall of the chimney breast, after which the thumb screw 14 is tightened. Then by lifting up the outer end of the holder you draw the point of the rod 18 upwardly about one-half or three-fourths of an inch higher than where it first struck. Now when the holder is pressed downwardly into position, the line formed by the holder, and the arm 18 has been straightened thus increasing the distance between the point of the rod 18 and the end of the holder thereby firmly pressing each into its niche in the respective walls of the chimney, it of course being understood that the niche for the rod 18 is formed in the breast of the chimney during the anchoring operation. The leaf spring 20 as hereinabove described affords a flexible adjustment by means of which the holder may be tilted vertically, after being so positioned to permit the insertion of the horizontal section of the pipe.

the stove pipe within the flue opening of the chimney, after which the said spring automatically returns the holder to its normal position which will be found to be immovably fixed between the walls of the chimney. The pipe of course is provided with the aforementioned screw bolts which enter the slot 5 of the outer member as the said pipe is being inserted in the flue opening, and with these parts so arranged the said screws are tightened thus rigidly connecting the said pipe and holder together. If additional sections to increase the length of the holder are to be used as shown in Fig. 7 the end of the second section telescopes within the first so as to be caught by the bolts 22 which when tightened makes a firm connection between the different sections of the holder.

While I have shown and described the preferred form of my invention, it is to be understood that I am not to be limited to the precise construction and arrangement of parts herein illustrated, as various changes may be made within the scope of the appended claims without departing from the spirit or nature of the invention.

What I claim is:—

1. A pipe holder comprising a member having a longitudinal slot, a second member slidably mounted therein, a breast engaging device mounted on the second member and having a portion extending through and terminating below said slot, the said second member being adjustable to bring said portion into engagement with the breast of the chimney, and means for holding said member in adjusted position.

2. A pipe holder comprising a member having a longitudinal slot, a second member slidably mounted therein, a breast engaging device mounted for rocking movement on said last mentioned member and having a portion extending through and terminating below said slot, said second member being adjustable to bring said portion into engagement with the breast of the chimney, and means for holding said member against sliding movement.

3. A pipe holder comprising a member having a longitudinal slot, a second member slidably mounted therein, a breast engaging device mounted for rocking movement on said last mentioned member and yieldably connected therewith, and having a portion extending through and terminating below said slot, said second member being adjustable to bring said breast engaging device into engagement with the chimney, and means for holding said member in adjusted position.

4. A pipe holder comprising a member having a longitudinal slot, a second member slidably mounted therein, means for holding said member against sliding movement, and a breast engaging device mounted on said

last mentioned member and having a portion extending through and terminating below said slot, said member being adjustable to bring said portion into engagement with the breast of the chimney, in combination with a pipe section having means slidable in said slot and adjustable against the member and operable to hold the latter and said pipe section connected with each other.

5. A pipe holder for chimneys comprising a member extending through the pipe opening in the breast of the chimney, means adjustably mounted on said member and extending into the vertical flue and lying against the breast thereof, and yieldable means bearing against the first means and operable to permit said member to be tilted thereon.

6. A pipe holder for chimneys comprising a member extending into the pipe opening in the breast of the chimney, a second member slidably mounted therein, means mounted on said second member and extending into the vertical flue and lying against the breast thereof, yieldable means bearing against the first means and operable to permit said member to be tilted and a retaining device carried by said second member and adjustable against the first member as described.

7. A pipe holder for chimneys comprising a member extending into the pipe opening in the breast of the chimney and traversing the vertical flue of the chimney, means on said member for engagement against the inner wall of the breast of the chimney to hold the member against movement in one direction, said member having one of its ends seated against the opposite wall of the chimney and held thereby against movement in another direction, and adjustable telescopic sections extending from said member.

8. A pipe holder for chimneys comprising a member extending through the pipe opening in the chimney and having a longitudinal slot, a second member slidably mounted therein, a breast engaging device mounted on said member and having a portion extending through and terminating below said slot in parallelism therewith, a removable handle carried by said last mentioned member and having a portion extending through said slot whereby to adjust said member to bring said breast engaging device into engagement with the chimney, and means for holding said member in adjusted position.

9. A pipe holder comprising a member having a longitudinal slot, a second member slidably mounted therein, a substantially Z-shaped rod carried by the second member and having a portion arranged within said outer member and a portion extended through and disposed below said slot in parallelism therewith, said second member being adjustable to bring said rod into engage-

ment with the breast of the chimney, and means for holding said member in its adjusted position.

10. A pipe holder comprising a member 5 extended through the pipe opening of the chimney and having a longitudinal slot, a second member slidably mounted therein, a substantially Z-shaped rod mounted for rocking movement on said member and having a portion arranged within said outer member and a portion extended through and disposed below said slot, a spring secured to

said second member and having its free end normally engaging said rod, said second member being adjustable to bring said rod 15 into engagement with the breast of the chimney, and means for holding said member in adjusted position.

In testimony whereof I affix my signature in presence of two witnesses.

JOHN W. JAMES.
